SASH CORNER JOINT CONSTRUCTION

Charles A. Pressnall, Elkhart, Ind., assignor to
The Adlake Company, Chicago, Ill., a corpora-
tion of Illinois

Application December 16, 1946, Serial No. 716,617

4 Claims. (Cl. 189—36)

1

My invention is concerned with improvements in window sash construction. More particularly, it relates to corner joint constructions for sash which are fabricated from relatively soft metal members such as aluminum sections or the like.

It is an object of my invention to provide an improved corner joint construction for window sash of relatively soft metal material which provides a simple yet effective corner joint having sufficient strength to withstand the hard usage to which such sash are subjected.

It is a further object of my invention to provide a corner joint construction for the frame members of metal sash wherein the end of one of the connecting frame members is provided with axially projecting tongues which extend through apertures in a side of the other frame member when the frame members are in abutting relation and a clincher or riveting plate of harder metal is provided against which the projecting tongues are bent over or clinched to secure the members in connected relation.

These and other objects and advantages will be apparent from a description of one embodiment of my invention which is shown, by way of illustration, in the accompanying drawings, wherein:

Fig. 1 is a perspective view of a top corner portion of a top sash member having a joint construction embodying the principles of my invention;

Fig. 2 is a longitudinal section, taken on the line 2—2 of Fig. 3;

Fig. 3 is a vertical section, taken on the line 3—3 of Fig. 2; and

Fig. 4 is an exploded view showing the end portions of the sash top and side rail members and the riveting plate.

In the fabrication of window sash from relatively soft metal members such as extruded aluminum sections, it has heretofore proven difficult to provide a corner joint construction which permits rapid assembly of the sash members and which has sufficient strength and rigidity to withstand the stresses to which the corner joint is subjected when the sash is installed and in use.

In my improved construction I provide a satisfactory corner connection between the frame members without the use of brazing or soldering which provides the desired strength and rigidity.

In the drawings I have shown my joint construction embodied in the top corner joint of a top sash where the side rail member is connected to the top rail member. The same principles may be applied to the corner connection between the side rail and the bottom rail or the side rail and the meeting rails.

2

In the illustrated embodiment the side rail 10 comprises a web portion 11 which extends longitudinally or axially of the rail and cooperates with a transverse end flange 12 and a lip or outside glazing bead 13 to form a shelf-like glazing portion for receiving the glass and putty (not shown). Transverse parallel flange portions 14 and 15 extend outwardly of the web portion 11 and are provided with oppositely directed channel-like grooves 16 and 17 which receive weather stripping (not shown). Flanges 14 and 15 are adapted to be slidably received in a guide channel provided in the jamb member. The flange 14 is provided on its outward face with an inwardly directed L-shaped member 18 which forms with the inner portion of the flange face a groove 19 for reception of the inside glazing bead member (not shown).

The top rail 20 which is illustrated happens to be tubular in section and includes a bottom wall or inner web portion 21 which cooperates with a vertical flange portion 22 and a lip or outside glazing bead 23 to form a shelf-like glazing portion for reception of the glass and putty (not shown). The vertical flange portion 22 constitutes an extension of the side wall or face 24 of the rail member 20. Along the opposite edge of the web portion 21 a spaced vertically extending wall portion 25 provides a groove or channel 26 for receiving the inside glazing bead member (not shown). The top wall or outer web portion 27 of the rail 20 is provided with an upstanding member 28 which is adapted to receive a weather stripping member for engagement in a sealing channel provided in the head molding. A reinforcing rib 29 extends upwardly or inwardly along the bottom wall 21 of the rail 20.

As more clearly illustrated in Fig. 4, the top rail 20 is provided at the end with longitudinally or axially projecting tongues 30, 31, 32 and 33. Tongues 30 and 31 are integral extensions of the rail web member 21 and reinforcing member 29 respectively. Tongues 32 and 33 are integral extensions of rail web member 27. The tongues 30, 31, 32 and 33 are conveniently formed when the end of the top rail 20 is cut or trimmed so that the end of each portion of the rail section will abut in the proper manner against the side of a section of the side rail 10 to form a neat and relatively close fitting joint.

The side rail 10 is trimmed or cut at its end to conform to the top of the top rail 20. A cut-out or aperture 34 is provided at the end of the web portion 11 and at a spaced distance from the end an L-shaped aperture 35 is provided. The apertures 35 and 34 receive the

tongues 30, 31, 32 and 33 which project from the top rail 20 when the side and top rail members 10 and 20 are brought into abutting relation. While the aperture 34 provided on the end of web portion 11 is illustrated as an open slot or recess, it may be a completely enclosed aperture of any shape desired, depending upon the shape of the tongues provided on the top rail 20. Likewise, the L-shaped aperture 35 provided in the end of web portion 11 may be any shape desired, depending upon the shape of the projecting tongues 30 and 31 on the top rail member 20. The projecting tongues 30, 31, 32 and 33 and the apertures 34 and 35 should be so shaped and so located that the tongues will pass through the apertures when the frame members are brought into abutting relation.

A riveting or clincher plate 36 is provided with an end recess or slot 37 and an L-shaped aperture 38 which correspond to the end slot 34 and L-shaped aperture 35, respectively, in the side rail member 10. The plate 36 is made of a material which is relatively hard, such as stainless steel, and is constructed of a size and shape which permits it to be positioned against the outer face of the web 11 of the side rail 10 with the projecting tongues 30, 31, 32 and 33 extending some distance beyond its outer face. With the clincher plate 36 in this position the projecting tongues 30, 31, 32 and 33 are clinched or bent over against the outer surface of the clincher plate 36 by the application of an appropriate tool. The clinching or bending over of the projecting tongues against the hard metal surface serves to tightly connect the side rail 10 and the top rail 20 with a joint which will absorb the stresses to which it is subjected when in use without becoming loose and permitting the sash members to break away from each other.

As illustrated in Fig. 4, the top rail member 20 is also provided with projecting lug members 39 and 40 which engage in the channel 49 in the side rail 10 when the frame members 10 and 20 are in abutting connected relation. The projections 39 and 40 are of sufficient size to snugly engage in the channel 49 and act as additional reinforcing or stiffening means between the frame members which serve to resist movement therebetween due to any laterally twisting to which the members may be subjected.

While I have referred to specific materials and details of construction in describing the illustrated embodiment of my invention, it will be understood that other materials and other details of construction may be resorted to within the scope of my invention.

I claim:

1. In a window frame corner joint construction, a vertical side frame member of relatively soft metal material having a web portion extending between front and back vertical flange portions, which web portion is provided with apertures extending horizontally and vertically adjacent the end thereof and laterally spaced from said vertical flange portions, a cross frame member of relatively soft metal material having an end thereof positioned in abutting relation with a side of said frame member, integral axially extending tongues on said end of said cross frame member, which tongues project through the apertures in said web portion of said side frame member and extend substantially beyond the outer surface of said web portion, and a relatively thin flat hard metal clincher plate, which clincher plate is provided with apertures inter-

mediate its edges which correspond substantially to the apertures in said web portion, said clincher plate being positioned with its inner face flat against the outer surface of said web portion and in edgewise engagement with a flange portion of the side frame member, the ends of said tongues being turned over into clinching relation with the outer face of said clincher plate whereby to permanently hold said frame members in rigid connected relation.

2. A sash corner joint construction comprising two sash frame members of relatively soft metal material, the end of the first frame member being arranged in abutting relation with the side of the second frame member, axial projecting integral lug formations extending at angles to each other and in spaced relation from the end of said first frame member, said second frame member having spaced side flange portions and a connecting web portion, said web portion being provided with apertures therein for receiving said projecting lug formations, and a thin flat clincher plate of relatively hard metal material positioned with its inner face flat against the outer surface of said web portion and in edgewise engagement with a side flange portion, said plate having apertures therein providing clinching edges in angular relation to each other, said lug formations having their ends extending beyond the outer face of said clincher plate and bent over in different directions about the clinching edges thereof and against said outer face whereby said clincher plate is securely and rigidly held against movement in all directions in the plane thereof and said sash frame members are connected together in permanent relation.

3. In a window frame corner joint construction, a vertical side frame member of relatively soft metal material having a web portion provided with vertically spaced angularly related apertures adjacent the end thereof, a cross frame member of relatively soft metal material having an end thereof positioned in abutting relation with a side of said side frame member, integral axially extending transversely spaced tongues on said end of said cross member, said tongues projecting through the vertically spaced apertures in said web portion of said side frame member and extending substantially beyond the outer surfaces of said web portion, and a relatively thin flat clincher plate of relatively hard metal material provided with apertures corresponding to the apertures in said web portion, said clincher plate being positioned with its inner face flatly against the outer surface of said web portion and being spaced inwardly from the ends of said projecting tongues, the ends of said tongues being turned over in different directions into clinching relation with the outer face of said clincher plate to permanently and rigidly secure said clincher plate against movement in all directions in the plane thereof and to hold said frame members in rigid connected relation.

4. A sash corner joint construction comprising two sash frame members formed of relatively soft metal material, the end of the first frame member being arranged in abutting relation with the side of the second frame member, axially projecting attaching lug formations and reinforcing lug formations extending in laterally spaced relation from the end of said first frame member, said second frame member having a glazing channel and an adjoining web portion provided with apertures therein for receiving said lug formations, which apertures are in an-

gular relation to each other, said reinforcing lug formations extending in relatively close fitting relation into said glazing channel and said attaching lug formations extending through said apertures, and a thin flat clincher plate of relatively hard metal material positioned with its inner face flat against said web portion adjacent said apertures, said projecting attaching lugs having their ends extending beyond the outer face of said clincher plate and bent over in different directions against the same whereby to permanently and rigidly secure said clincher

plate against movement in all directions in the plane thereof and to securely connect said sash frame members together in rigid relation.
